UNITED STATES PATENT OFFICE

137,734

DESIGN FOR A CHECK WRITING MACHINE CASING

Merritt G. Stewart, Chicago, Ill.

Application March 3, 1944, Serial No. 112,777

Term of patent 14 years

(Cl. D74—1)

To all whom it may concern:

Be it known that I, Merritt G. Stewart, a citizen of the United States, residing at Chicago, in the county of Cook and State of Illinois, have invented a new, original, and ornamental Design for a Check Writing Machine Casing, of which the following is a specification, reference being had to the accompanying drawing, forming a part thereof, and wherein:

I claim:

The ornamental design for a check writing machine casing, as shown.

MERRITT G. STEWART.
